LAWN MOWER FOR GOLF COURSE GREENS AND THE LIKE

Donald O. Benson, Minneapolis, Minn., assignor to Toro
Manufacturing Corporation, Minneapolis, Minn., a
corporation of Minnesota

Filed Jan. 26, 1959, Ser. No. 54,330

Term of patent 14 years

(Cl. D40—1)

FIG. 1 is a front and side perspective view of a lawn
mower for golf course greens and the like, showing my
new design;

FIG. 2 is a reduced left side elevational view thereof,
a portion of the handle broken away for convenience of
illustration; and

FIG. 3 is a top plan view of FIG. 2.

The dominant features of the design reside in the full
line portions shown in the drawing.

I claim:

The ornamental design for a lawn mower for golf
course greens and the like, as shown and described.
